UNITED STATES PATENT OFFICE.

JOHN E. NORWOOD, OF SYKESVILLE, MARYLAND, ASSIGNOR OF ONE-HALF
TO CHARLES R. FAVOUR, OF SAME PLACE.

CAR-REPLACER.

SPECIFICATION forming part of Letters Patent No. 257,827, dated May 9, 1882.

Application filed March 23, 1882. (No model.)

To all whom it may concern:

Be it known that I, JOHN E. NORWOOD, a citizen of the United States, and resident of Sykesville, in the county of Carroll and State 5 of Maryland, have invented a new and valuable Improvement in Car-Replacers; and I do hereby declare that the following is a full, clear, and exact description of the construction and operation of the same, reference being had to the annexed drawings, making a 10 part of this specification, and to the letters and figures of reference marked thereon.

Figure 1 of the drawings is a representation of a railroad, showing my improvement 15 attached. Fig. 2 is a cross-sectional view of the same. Fig. 3 is a side view of the replacer. Fig. 4 is a similar view, and Fig. 5 is a bottom view of the same. Fig. 6 is a sectional detail view.

20 This invention has relation to devices for replacing derailed cars on the track; and it consists in the construction and novel arrangement of the centrally and obliquely ridged plates, slanting laterally toward the rail-edge and inclined toward each end longitudinally, the latter inclination and the lateral slant 25 easily merging into each other, the center post or support under the ridge, its holding point or spike, and the longitudinal rabbet or 30 groove under the rail-edge of the plate, all as hereinafter set forth. These plates are usually employed in pairs—one on the outside of one rail and the other on the inside of the opposite rail. The general formation of the 35 two plates is similar; but they differ in regard to special features, as will be hereinafter explained.

In the accompanying drawings, the letter 40 A designates the outside replacer-plate, and B the inside plate. Each plate is formed with a central oblique rise or ridge, C, which slants downward toward the rail-edge d. From the ridge C the face of the plate inclines toward each end, as indicated at e, the 45 back edge, g, of the plate being always higher than the front edge, d, which is adjusted to the rail. Under the central ridge, C, is formed a pillar or support, H, which is designed to rest on the tie, and is provided with a spur or 50 spike, k, to engage the tie and hold the plate

in position. Spurs or spikes may also be provided under the plate, near each end; or, notches may be formed in the ends of the plate, to engage spikes which may be driven into the ties. The rail-edge d of each plate is 55 grooved or rabbeted longitudinally underneath, as shown at m, to afford a raised edge bearing or extension to fit over the flange of the rail, covering the heads of the rail-spikes. Each way from the center post under the ridge 60 the plate is made comparatively thin, so that it can be easily transported, the wing portions being designed to be as light as possible consistent with the necessary strength. The rail-edge of the outside plate is centrally higher 5 than the inside plate, and just back of said edge a valley or groove, v, is formed to receive and guide the flange of the wheel, which, as the car moves forward, rolls in the groove upward toward the ridge, which, although its 70 lateral slope is steep, is obtusely rounded from end to end. Therefore, although the weight of the car is on the flange of the wheel bearing in the groove v of the plate until the flange is raised to the level of the top of the rail, the 75 bearing is then transferred to the tread of the wheel and the rounded inclined slope of the plate to lift the flange over the rail to the inside thereof. The inside plate, B, is usually 80 made wider than the outside plate. The slope of this plate is not rounded longitudinally over the ridge, as in the outside plate, but runs up rather sharply and quickly, forming a more defined ridge, as shown in the drawings. While the outside piece will sustain the weight in 85 replacing a car near its rail-edge, the inside plate will be engaged further from its rail-edge, and therefore should be made comparatively 90 thicker in the wing portions. In forming the outside plate the under groove at the edge 95 next the rail does not extend entirely to the end of the plate, because the plate is notched at each end to fit the flange closely, and at the same time to provide a bevel surface as near as possible to the flange of the rail for the reception of the flange of the wheel.

Having described this invention, what I claim, and desire to secure by Letters Patent, is—

1. The car-replacer consisting of a plate centrally and obliquely ridged, at C, and inclined 100

toward each end, as at *e*, the center post or support, *H*, its holding point or spike *k*, and the rabbet or groove *m* under the projecting edge *d*, substantially as specified.

5 2. The outside replacer-plate having the central oblique ridge, *C*, rounded from end to end and merging into the oblique inclines *e* toward each end, the projecting undergrooved edge *d*, the valley or groove *v* in the upper surface,

back of said edge, and the center support, *H*, 10 substantially as specified.

In testimony that I claim the above I have hereunto subscribed my name in the presence of two witnesses.

JOHN E. NORWOOD.
